UNITED STATES PATENT OFFICE.

WILLIAM HENRY TURNER, OF INDIANAPOLIS, INDIANA.

HEATER.

SPECIFICATION forming part of Letters Patent No. 558,124, dated April 14, 1896.

Application filed February 14, 1893. Serial No. 462,232. (No model.)

To all whom it may concern:

Be it known that I, WILLIAM HENRY TURNER, of Indianapolis, in the county of Marion and State of Indiana, have invented certain new and useful Improvements in Heaters; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

The main objects of my invention are to improve the draft and combustion of the heater and to provide for ventilation and the distribution of heat and the removal of dust in connection therewith.

It consists, essentially, of certain novel features in the construction and arrangement of component parts of the heater, and particularly of the draft and ventilating connections hereinafter particularly described, and pointed out in the claims.

In the accompanying drawings like letters designate the same parts in both figures.

Figure 1 is a vertical medial section of a hot-air furnace or heater to which my improvements are applied; and Fig. 2 is a cross-section on the line 2 2; Fig. 1, of the double draft and ventilating flue.

Referring to Fig. 1 of the drawings, A represents the fire-pot; B, the ash-pit; C, the combustion-chamber; D, the dome; E, the door-opening or passage into the combustion-chamber; F, the door-opening or passage into the ash-pit, and G the smoke-flue or pipe leading out of the dome D.

The fire-pot A is preferably contracted toward its upper end, so as to confine the gases given off by the fuel until they are thoroughly consumed. It is formed or provided on one side with a passage separated therefrom by a partition *a* and opening at its upper end at *a'* into the upper portion of the fire-pot. At its lower end this passage is closed by a damper or removable plate *m*⁵, or in any other suitable manner, which permits of dropping any ashes, dust, or dirt which may collect in said passage into the ash-pit B.

H is a vertical flue divided lengthwise by a partition *h* into a ventilating-passage *h'* and

draft-passage *h*², both opening at their upper ends into the smoke-flue G, the ventilating-passage connecting at the lower end with an elbow *H'*, which leads out through the base of the heater and opens near the floor into the apartment in which the heater is placed or connects with the lower end of a pipe *H*², leading downwardly from a register or opening (not shown) in the floor of the apartment above.

I is a connection between the draft-passage *h*² and the upper part of the ash-pit B. It is provided with a damper *i*. K is a similar connection between the draft-passage *h*² and the downdraft-passage at the back of the fire-pot. It is provided with a damper *k*. A similar connection L is provided between the combustion-chamber C and the flue H. It is provided at its junction with passage *h*² with a damper *l*, whereby communication may be opened or closed between the combustion-chamber and the ventilating-passage *h'*, the partition *h* being omitted or cut away opposite said damper. When said damper is turned upwardly, as shown in Fig. 2, it partially closes the passages *h'* and *h*² above the connection L, thereby serving as a deflector to turn a portion of the air ascending in passage *h'* into the combustion-chamber through said connection L. Between the upper end of the flue H and the dome D the smoke-flue G is provided with a damper *g*.

M is the grate, supported at the edges and capable of being turned horizontally upon lugs *b b*, projecting inwardly from the base of the fire-pot or top of the ash-pit. The rim of the grate is formed on the front side with a socket or other device *m*⁴ to receive a shaking-handle.

To prevent the gases and products of combustion, with the heat carried thereby, from passing directly from the combustion-chamber and dome of the heater into the smoke-flue, I provide a deflector N in the dome a short distance from the opening into the smoke-flue, leaving a space entirely around it between its edges and the adjacent walls of the dome, through which space said gases, products of combustion, and the heat which they contain are compelled to pass before they can escape from the heater. Said deflector is set at an angle, as shown, to turn or double

the flames back upon themselves. Perfect combustion of the fuel is thus promoted and the waste of heat prevented.

For convenience of illustration I have shown 5 my improvements in connection with a hot-air furnace which is designed to be inclosed by a casing, as shown in Fig. 1; but they are equally applicable to other kinds of heaters.

My improved heater operates as follows: 10 When the fire is low or newly kindled and a strong draft is required, the dampers in the ash-pit door and in the smoke-flue are opened, and the draft connection between the combustion-chamber C and flue H is closed by the 15 damper l, the dampers i and k being also closed in the connections I and K. When the fuel is well ignited, the damper l may be turned to open the connection L into flue H and to partially close communication between 20 the ventilating-passage h' and the smoke-flue, thereby directing air into the combustion-chamber over the fire and supplying oxygen, which facilitates combustion and completely consumes the combustible products given off 25 from the fuel. By this means air is drawn from the colder impurer strata near the floor of the apartment in which the heater is placed or of the apartment out of which the pipe H² leads, thereby affording ventilation, and at 30 the same time producing complete and perfect combustion by supplying the necessary oxygen to the unconsumed inflammable products given off by the fuel. When it is wished to check the draft and maintain a slow fire, 35 the smoke-flue damper g is closed and the damper k opened, thereby establishing indirect communication between the upper part of the fire-pot and the smoke-flue through the downdraft-passage, the connection K, and the 40 draft-passage h². The connection L between the flue H and the combustion-chamber C may also be closed, thereby depriving the fire of oxygen and further checking combustion. When the connection L is closed by the damper l, communication will be unobstructed 45 between the ventilating-passage h' and the smoke-flue, and the apartment in which the heater is placed or with which the pipe H² is connected will be ventilated, as before, the 50 cooler and impurer air being drawn from a point near the floor and carried into the smoke-flue. When the grate is shaken or ashes removed from the ash-pit B, the damper i should be opened, thus allowing the dust to 55 be drawn through the connection I and the draft-passage h² into the smoke-flue G. At other times, however, the damper i should be kept closed.

To permit of the heat being thrown directly 60 out into the room or apartment in which the heater is located, or to enable a person to warm himself directly therefrom, I provide in one or more openings in the double casing into the hot-air space one or more vertically- 65 movable doors N, which are connected by chains or cords n, passing over pulleys o in

the inner wall of said casing, with counter-weights O, which are thus hidden from view. P is the water-pan.

Various changes in the details of construction and arrangement of parts hereinbefore mentioned may be made within the intended spirit and scope of my invention.

I claim—

1. In a heater the combination with the smoke-flue leading out of the upper part of the heater, of a ventilating-flue opening at its upper end into said smoke-flue and having an air-intake opening or connection at or near its lower end, and a connection with the heater 8c between the smoke-flue and the grate, substantially as and for the purposes set forth.

2. In a heater the combination with the smoke-flue connected with the upper part of the heater, of a ventilating-flue opening at its upper end into said smoke-flue and having an air-intake opening or connection at or near its lower end, and a damper-controlled connection leading downwardly out of the combustion-chamber of the heater above the fuel-level into said ventilating-flue below the smoke-flue, substantially as and for the purposes set forth.

3. In a heater the combination with the smoke-flue leading out of the upper part of the heater, of a ventilating-flue opening at its upper end into said smoke-flue and having an air-intake opening or connection at or near its lower end, a connection between said flue and the combustion-chamber of the heater, and a damper controlling communication between said flue and combustion-chamber, and arranged to direct air from said flue into the combustion-chamber when desired, substantially as and for the purposes set forth.

4. In a heater, the combination with the smoke-flue having a damper-controlled connection with the upper part of the heater, of a ventilating-flue connected at its upper end with said smoke-flue and having an air-intake opening or connection at or near its lower end, the fire-pot provided on one side with a downdraft-passage, a flue leading out from said passage into said ventilating-flue and provided with a damper, substantially as and for the purposes set forth.

5. In a heater, the combination with the smoke-flue and ash-pit of a flue divided longitudinally by a partition into draft and ventilating passages, opening at their upper ends into the smoke-flue, the ventilating-passage having an air-intake opening or connection at or near its lower end, and a connection provided with a damper between the draft-passage and the ash-pit, substantially as and for the purposes set forth.

6. In a heater, the combination with the smoke-flue and fire-pot, provided with a downdraft-passage, of a flue divided into draft and ventilating passages opening at their upper ends into the smoke-flue, the ventilating-passage having an intake opening or connection

at or near its lower end, a connection provided with a damper between said downdraft-passage and the draft-passage of said flue, and a connection provided with a damper between the combustion-chamber of the heater and the ventilating-passage of said flue, substantially as and for the purposes set forth.

7. In a heater, the combination with the smoke-flue, fire-pot provided with a down-draft-passage, ash-pit and combustion-chamber, of a flue divided into draft and ventilating passages opening at their upper ends into the smoke-flue, the ventilating-passage having an intake opening or connection at or near its lower end, a connection provided with a damper between said draft-passage and the ash-pit, a connection provided with a damper between said draft-passage and the down-draft-passage of the fire-pot, and a connection provided with a damper between the ventilating-passage and the combustion-chamber, substantially as and for the purposes set forth.

8. In a heater, the combination with the smoke-flue connected with the upper part of the heater, of an upward-draft flue opening at its upper end into said smoke-flue, a down-draft-passage opening at its upper end into the fire-pot, and at its lower end, which is provided with a movable section, into the ash-pit, a damper-controlled connection between the lower end of said passage and the upward-draft flue, and a damper in the smoke-flue between the heater and said upward-draft flue, substantially as and for the purposes set forth.

9. In a heater, the combination with the smoke-flue, fire-pot provided with a down-draft-passage opening into the upper part

thereof, and combustion-chamber, of a flue divided into draft and ventilating passages opening at their upper ends into the smoke-flue, the ventilating-passage having an intake connection or opening at its lower end near the base of the heater, a connection provided with a damper between the downdraft-passage of the fire-pot and the draft-passage of said flue, a connection provided with a damper between the combustion-chamber and the ventilating-passage of said flue, and a damper in the smoke-flue between the heater and the upper end of the draft and ventilating flue, substantially as and for the purposes set forth.

10. In a heater, the combination with the dome and smoke-flue leading laterally out of the same, of a deflector placed at an inclination to a vertical plane in said dome opposite the opening into the smoke-flue, with a space between its edges and the walls of the dome extending entirely around the deflector, substantially as and for the purposes set forth.

11. In a heater the combination with a casting inclosing a hot-air space around the heater proper and having one or more openings into said hot-air space, of one or more vertically-movable doors and counterweights connected therewith by cords or chains passing over pulleys above said openings, substantially as and for the purposes set forth.

In testimony that I claim the foregoing as my own I affix my signature in presence of two witnesses.

WILLIAM HENRY TURNER.
